US00D601185S

(12) **United States Design Patent**
Kim et al.

(10) **Patent No.:** US D601,185 S
(45) **Date of Patent:** ** Sep. 29, 2009

(54) **LASER PRINTER**

(75) Inventors: **Hee-Yul Kim**, Kyunggi-do (KR);
Kwang-Soo Ha, Seoul (KR);
Min-Hyoug Boo, Seoul (KR); **Yun-Gi Hong**, Kyunggi-do (KR)

(73) Assignee: **Samsung Electronics Co., Ltd.**,
Kyunggi-do (KR)

(**) Term: **14 Years**

(21) Appl. No.: **29/294,093**

(22) Filed: **Dec. 21, 2007**

(51) **LOC (9) Cl.** **14-02**

(52) **U.S. Cl.** **D18/50**

(58) **Field of Classification Search** D18/36-39,
D18/50, 54, 54.1, 55; D14/420-425, 462-470;
400/613, 613.1-613.4, 690.1-690.4, 691-694

(57) **CLAIM**

The ornamental design for a laser printer, as shown and described.

DESCRIPTION

FIG. 1 is a top front perspective view of a laser printer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
